Fred C. Sproul, P.O. Box 1038,
Oceanside, Calif. 92054

Filed Jan. 11, 1967, Ser. No. 5,382

Term of patent 14 years

(Cl. D13—1)

FIG. 1

FIG. 2.

FIG. 1 is a perspective view illustrating the housing tract of the invention;

FIG. 2 is a top plan view of the tract.

Dominant features of the design are shown in solid lines namely the configuration of the back fence, the relative size of the houses and lots, and the arrangement of the houses with respect to each other and the front and back boundaries.

I claim:

The ornamental design for a housing tract, as shown and described.
